(57) **CLAIM**

I claim the ornamental design for a horticultural pot, as shown and described.

DESCRIPTION

FIG. 1 is a top perspective view of a horticultural pot;

FIG. 2 is a bottom perspective view thereof;

FIG. 3 is a bottom plan view thereof;

FIG. 4 is a top plan view thereof;

FIG. 5 is a left side elevation view thereof; and,

FIG. 6 is a front elevation view thereof.

The broken lines depict environmental subject matter only and form no part of the claimed design.
